(57) **CLAIM**

The ornamental design for a canister, as shown and described.

DESCRIPTION

FIG. 1 is a perspective view of a canister, according to an embodiment of the disclosed subject matter.

FIG. 2 is a rear view of the canister of FIG. 1, according to an embodiment of the disclosed subject matter.

FIG. 3 is a front view of the canister of FIG. 1, according to an embodiment of the disclosed subject matter.

FIG. 4 is a left side view of the canister of FIG. 1, according to an embodiment of the disclosed subject matter.

FIG. 5 is a right side view of the canister of FIG. 1, according to an embodiment of the disclosed subject matter.

FIG. 6 is a top plan view of the canister of FIG. 1, according to an embodiment of the disclosed subject matter.

FIG. 7 is a bottom plan view of the canister of FIG. 1, according to an embodiment of the disclosed subject matter.

FIG. 8 is a perspective view of a canister, according to an embodiment of the disclosed subject matter.

FIG. 9 is a rear view of the canister of FIG. 8, according to an embodiment of the disclosed subject matter.

FIG. 10 is a front view of the canister of FIG. 8, according to an embodiment of the disclosed subject matter.

FIG. 11 is a left side view of the canister of FIG. 8, according to an embodiment of the disclosed subject matter.

FIG. 12 is a right side view of the canister of FIG. 8, according to an embodiment of the disclosed subject matter.

FIG. 13 is a top plan view of the canister of FIG. 8, according to an embodiment of the disclosed subject matter; and,

FIG. 14 is a bottom plan view of the canister of FIG. 8, according to an embodiment of the disclosed subject matter. The broken lines in the drawings illustrate the portions of the canister that form no part of the claim.

1 Claim, 14 Drawing Sheets
